CLAIM

The ornamental design for a frying pan or similar article, substantially as shown and described.

DESCRIPTION

FIG. 1 is a top plan view of a frying pan or similar article showing my new design;

FIG. 2 is a right side elevational view thereof, the left side being a mirror image thereof;

FIG. 3 is a bottom plan view thereof, with the flutes partially shown for convenience of illustration;

FIG. 4 is a front elevational view thereof; and

FIG. 5 is a rear elevational view thereof.

FIG. 1.

FIG. 2.

FIG. 3.

FIG. 4.

FIG. 5.
